TWO-CYCLE ENGINE AXIAL SCAVENGING OF CYLINDERS

Filed Oct. 31, 1945

UNITED STATES PATENT OFFICE

2,516,228

TWO-CYCLE ENGINE AXIAL SCAVENGING
OF CYLINDERSNathaniel Macy and George F. Schafer,
Greencastle, Ind.

Application October 31, 1945, Serial No. 625,756

9 Claims. (Cl. 123—65)

1

This invention relates to a V-type two cycle internal combustion engine.

The chief object of this invention is to improve the operating characteristics and increase the power output of such an engine.

The chief feature of this invention resides in an air compressor common to both V-arranged cylinders and cylindrically operable in dual relation to any power piston operation, and in positively supplying fuel at a predetermined portion of the piston cycle to the associated cylinder.

Another feature of the invention resides in the simultaneous air and fuel control whereby throttling is accomplished without substantial variation of fuel-air ratio.

Other objects and features the invention will be set forth more fully hereinafter.

The full nature of the invention will be understood from the accompanying drawings and the following description and claims:

In the drawings Fig. 1 is a semi-diagrammatic transverse sectional view of a V-arranged multiple cylinder engine with an interposed singular air compressor, the crank case and crank shaft bearings being omitted for clearness.

Fig. 2 is a longitudinal sectional view of the fuel supply nozzle and an elevational view of the power and control associated parts.

Fig. 3 is an enlarged central sectional view of a check valve in the fuel supply line that is suction operable by injection plunger retraction and is plunger pressure seatable.

In Fig. 1 of the drawings 10 indicates a power cylinder, water-jacketed for cooling as at 11 and having therein power piston 12. The two cylinders illustrated are shown in V-arrangement and therebetween is an air compressor cylinder 13 in which is mounted air piston 14.

Each power piston has water-jacketed head 15 provided with exhaust conduit 16 controlled by poppet valve 17 normally constrained by its spring 18 to seat 19. Stem 20 is rocker arm actuated, 21 indicating the rocker, and 22 generally indicating the tappet and tappet guide, etc. Rocker arm 21 is supported at 23 upon the head and all the aforesaid may be enclosed as at 24. Plug 25 is also head mounted.

Herein a cam shaft 26 includes cam 27 that successively engages followers 28 of the tappet structure. 29 indicates the crank shaft having eccentric portions 30 to which are connected rods 31, in turn connected by wrist pins 32 to the power pistons 12. The two portions 30 have the relative positions as shown, that is, same are 33

displaced approximately 90°. Note also that the followers 28 are displaced about 90° so that single cam 27 can successively actuate each.

Each power cylinder 10 near the end of the piston stroke, see left hand cylinder in Fig. 1, includes an annular channel 33 having free communication with the cylinder by ports 34. Conduits 35 connect the channels 33 to the air cylinder 13. Obviously, when power piston 12 is compressing or final scavenging the ports 34 are cut off by said piston from cylinder 11 communication.

The air supply includes valve seat 36 in the head end of cylinder 13 controlled by valve 37 light spring constrained to closed position. This is a check valve and opens on suction in cylinder 13 and closes upon pressure therein.

Enveloping the head end of the air cylinder 13 is hood or air intake manifold 38 which has an intake opening 38a, but said intake is controlled by butterfly valve 39 therein and on shaft 40 that, externally of the manifold, mounts pinion 41 meshing with rack 42.

Air compressor piston 14 includes rod 43 guided as at 44 and said stem at its outer, lower free end mounts follower roll 45. Associated with the stem is spring 46 normally constraining the piston to suction action and the follower to engagement with cam 47 carried by the crank shaft 29. This cam has a gradual elevation portion 48 and a quick drop portion 49.

The cam illustrated is of dual character so that for each revolution of the crank shaft piston 14 is twice reciprocated. From the foregoing it is obvious that piston 14 is quickly lowered by spring 46 when cam freed, as it were, to suck in air past check valve 37, which opens upon suction, and from the air manifold or header controlled by air valve 39.

When the suction stroke is completed the piston 14 is cam actuated to compress the air trapped in cylinder 13, and this compressed air is supplied by conduits 35 to annular channels 33 about the power cylinders 10.

If the power piston 12 is sufficiently lowered due to a previous combustion stroke, the ports 34 will be uncovered and the compressed air will discharge to cylinder 10. Exhaust valve 17 having opened, it will be clear that the exhaust gases are blown out passage 16 by the inrushing new air charge.

When sufficient scavenging occurs and before fuel intake occurs exhaust valve 17 is closed and air under pressure is supplied to the cylinder 10 for combustion purposes until the rising pis-

ton 12 cuts off ports 34. The air trapped in the power cylinder is then compressed to the volume shown in the right end of Fig. 1, whereupon at dead center, or slightly before or after as desired, and determined by a timer mechanism (not shown) operable from the cam shaft 26 supplies a spark at plug 28. Upon ignition of the combustible mixture, the power stroke of the piston 12 is effected.

Reference will now be had more particularly to Fig. 2 wherein the pressure fuel supply is illustrated. The cam shaft 26 has cam 60 thereon that engages follower roll 61 carried by arm 62 pivoted at 63 and engaging piston rod 65 slideable in bore 66 of nozzle 67.

This nozzle has a fuel supply 68 leading to a check valve 69 in turn feeding to conduit 70 opening into tip 71 which has outlet 72 registering with port 73 in cylinder wall 10. For clearness only, ports 73 are illustrated in Fig. 1.

The nozzle 67 has threaded chamber 64 coaxial with bore 66. Threaded therein is thimble 75 with inner closed end 76 that is apertured to slidably support plunger stem 65. A coil spring 77 bears against end 76 and is retained by retainer 78 adjustably mounted on stem 65.

When follower 61 is not engaged with cam 60 the spring 77 tilts arm 62 counter-clockwise on pivot 63 and retracts the plunger 65 in bore 66. Upon this retraction fuel is drawn through the check valve 69, see Fig. 3, to the nozzle tip chamber 71 and that part of the bore 66 vacated by the plunger.

When follower 61 is engaged by cam 60, lever 62 is tilted clockwise and plunger 65, against spring 77, is forced toward the tip. In so doing check valve 69 is automatically seated and the fuel, now under pressure, is discharged at port 73 to the power cylinder 10.

Thimble 75 on its nozzle exposed end mounts a pinion 80 that meshes with rack 42 aforesaid and the thimble by rack reciprocation through pinion 80 is caused to further nest in chamber 64 of the nozzle or project therefrom, thus determining the amount of fuel pumped.

Also, the fuel and air is simultaneously varied, that is, increased or decreased so that fuel to air ratio is substantially constant. Rack 42 may be foot or hand throttle actuated and, obviously, for self-propelled vehicles would be set for low idle at minimum supply. Starting and stopping may then be effected by ignition circuit control to the plugs through a master switch, not shown.

While the invention has been illustrated and described in great detail in the drawings and foregoing description, the same is to be considered as illustrative and not restrictive in character.

The several modifications described herein, as well as others which will readily suggest themselves to persons skilled in this art, all are considered to be within the broad scope of the invention, reference being had to the appended claims.

The invention claimed is:

1. In a two cycle engine having a relatively stationary power cylinder and a piston therein, the cylinder having air intake ports near the end of the stroke, and poppet type exhaust valve means operable in timed relation with piston travel, the combination of air compressing, auxiliary means operable in timed relation to piston operation and communicating with said ports, and fuel supplying means communicating with the cylinder near the intake end thereof and

also operable in timed relation to piston operation, the timing being such that compressed air from the auxiliary means initially scavenges the cylinder prior to fuel supply thereto.

5. In a two-cycle engine having a power cylinder and piston, the cylinder having air intake ports near the end of the stroke and exhaust means operable in timed relation with piston travel, the combination of air compressing, engine operable, means operable in timed relation to piston operation and communicating with said ports, and fuel supplying means communicating with the cylinder and also operable in timed relation to piston operation, the timing being such that compressed air initially scavenges the cylinder prior to fuel supply thereto, and means simultaneously regulating fuel and air intake for engine control at substantially constant predetermined fuel to air ratio.

20. 3. In a two-cycle engine having a power cylinder and piston, the cylinder having air intake ports near the end of the stroke and exhaust means operable in timed relation with piston travel, the combination of air compressing, engine operable, means operable in timed relation to piston operation and communicating with said ports, and fuel supplying means communicating with the cylinder and also operable in timed relation to piston operation, the timing being such that compressed air initially scavenges the cylinder prior to fuel supply thereto, and means simultaneously regulating fuel and air intake for engine control at substantially constant predetermined fuel to air ratio.

25. 3. In a two-cycle engine having a power cylinder and piston, the cylinder having air intake ports near the end of the stroke and exhaust means operable in timed relation with piston travel, the combination of air compressing, engine operable, means operable in timed relation to piston operation and communicating with said ports, and fuel supplying means communicating with the cylinder and also operable in timed relation to piston operation, the timing being such that compressed air initially scavenges the cylinder prior to fuel supply thereto, the fuel supplying means including a nozzle, a plunger reciprocable therein normally constrained to movement in one direction, engine operable means for timed movement of the plunger in the opposite direction and in opposition to the constraint, said nozzle having a tip discharge to the engine cylinder and a check valve controlled fuel supply to the nozzle.

40. 4. In a two-cycle engine having a power cylinder and piston, the cylinder having air intake ports near the end of the stroke and exhaust means operable in timed relation with piston travel, the combination of air compressing, engine operable, means operable in timed relation to piston operation and communicating with said ports, and fuel supplying means communicating with the cylinder and also operable in timed relation to piston operation, the timing being such that compressed air initially scavenges the cylinder prior to fuel supply thereto, the fuel supplying means including a nozzle, a plunger reciprocable therein normally constrained to movement in one direction, engine operable means for timed movement of the plunger in the opposite direction and in opposition to the constraint, said nozzle having a tip discharge to the engine cylinder, a check valve controlled fuel supply to the nozzle, and means interposed between the nozzle and plunger for regulating the stroke thereof for fuel variation.

45. 5. In a two-cycle engine having a power cylinder and piston, the cylinder having air intake ports near the end of the stroke and exhaust means operable in timed relation with piston travel, the combination of air compressing, engine operable, means operable in timed relation to piston operation and communicating with said ports, and fuel supplying means communicating with the cylinder and also operable in timed relation to piston operation, the timing being such that compressed air initially scavenges the cylinder prior to fuel supply thereto, the air supplying means including a cylinder, a valve controlled intake thereto, said air cylinder freely commu-

50. 5. In a two-cycle engine having a power cylinder and piston, the cylinder having air intake ports near the end of the stroke and exhaust means operable in timed relation with piston travel, the combination of air compressing, engine operable, means operable in timed relation to piston operation and communicating with said ports, and fuel supplying means communicating with the cylinder and also operable in timed relation to piston operation, the timing being such that compressed air initially scavenges the cylinder prior to fuel supply thereto, the air supplying means including a cylinder, a valve controlled intake thereto, said air cylinder freely commu-

55. 6. In a two-cycle engine having a power cylinder and piston, the cylinder having air intake ports near the end of the stroke and exhaust means operable in timed relation with piston travel, the combination of air compressing, engine operable, means operable in timed relation to piston operation and communicating with said ports, and fuel supplying means communicating with the cylinder and also operable in timed relation to piston operation, the timing being such that compressed air initially scavenges the cylinder prior to fuel supply thereto, the air supplying means including a cylinder, a valve controlled intake thereto, said air cylinder freely commu-

60. 7. In a two-cycle engine having a power cylinder and piston, the cylinder having air intake ports near the end of the stroke and exhaust means operable in timed relation with piston travel, the combination of air compressing, engine operable, means operable in timed relation to piston operation and communicating with said ports, and fuel supplying means communicating with the cylinder and also operable in timed relation to piston operation, the timing being such that compressed air initially scavenges the cylinder prior to fuel supply thereto, the air supplying means including a cylinder, a valve controlled intake thereto, said air cylinder freely commu-

nicating with the power cylinder ports, and piston means in the air cylinder for charging thereof and compressing the air trapped in the air cylinder.

6. In a two-cycle engine having a power cylinder and piston, the cylinder having air intake ports near the end of the stroke and exhaust means operable in timed relation with piston travel, the combination of air compressing, engine operable, means operable in timed relation to piston operation and communicating with said ports, and fuel supplying means communicating with the cylinder and also operable in timed relation to piston operation, the timing being such that compressed air initially scavenges the cylinder prior to fuel supply thereto, the air supplying means including a cylinder, a valve controlled intake thereto, said air cylinder freely communicating with the power cylinder ports, and piston means in the air cylinder for charging thereof and compressing the air trapped in the air cylinder, the air piston being normally constrained to movement in one direction and engine power movable in the opposite direction.

7. In a two-cycle engine having a power cylinder and piston, the cylinder having air intake ports near the end of the stroke and exhaust means operable in timed relation with piston travel, the combination of air compressing, engine operable, means operable in timed relation to piston operation and communicating with said ports, and fuel supplying means communicating with the cylinder and also operable in timed relation to piston operation, the timing being such that compressed air initially scavenges the cylinder prior to fuel supply thereto, the air supplying means including a cylinder, a valve controlled intake thereto, said air cylinder freely communicating with the power cylinder ports, and piston means in the air cylinder for charging thereof and compressing the air trapped in the air cylinder, an air intake manifold for said air cylinder, the intake being included therebetween, the manifold having an intake opening to atmosphere, and valve means for controlling the amount of second mentioned intake opening.

8. In a two-cycle engine having a power cylinder and piston, the cylinder having air intake ports near the end of the stroke and exhaust means operable in timed relation with piston travel, the combination of air compressing, engine operable, means operable in timed relation to piston operation and communicating with said ports, and fuel supplying means communicating with the cylinder and also operable in timed relation to piston operation, the timing being such that compressed air initially scavenges the cylinder prior to fuel supply thereto, the air supply-

ing means including a cylinder, a valve controlled intake thereto, said air cylinder freely communicating with the power cylinder ports, and piston means in the air cylinder for charging thereof and compressing the air trapped in the air cylinder, an air intake manifold for said air cylinder, the intake being included therebetween, the manifold having an intake opening to atmosphere, and valve means for controlling the amount of second mentioned intake opening, said valve means being of butterfly type.

9. In a two-cycle engine having a power cylinder and piston, the cylinder having air intake ports near the end of the stroke and exhaust means operable in timed relation with piston travel, the combination of air compressing, engine operable, means operable in timed relation to piston operation and communicating with said ports, and fuel supplying means communicating with the cylinder and also operable in timed relation to piston operation, the timing being such that compressed air initially scavenges the cylinder prior to fuel supply thereto, the air supplying means including a cylinder, a valve controlled intake thereto, said air cylinder freely communicating with the power cylinder ports, and piston means in the air cylinder for charging thereof and compressing the air trapped in the air cylinder, an air intake manifold for said air cylinder, the intake being included therebetween, the manifold having an intake opening to atmosphere, and valve means for controlling the amount of second mentioned intake opening, said valve means being of butterfly type, the air piston being normally constrained to movement in one direction and engine power movable in the opposite direction.
